TIME SWITCH

Walter C. Padgett, Kansas City, Mo.

Application February 9, 1938, Serial No. 189,584

7 Claims. (Cl. 200—38)

This invention relates to time switches of the character usable in connection with the conventional type radio and may be used in such a location to automatically turn the radio on or off at a predetermined set time, or to automatically first turn on the radio and then after the same has operated for a desired length of time, to then turn off the set so that the owner thereof will not be required to give attention after the time switch embodying this invention has once been set.

The primary object of this invention is to provide a time switch susceptible of fulfilling the aforementioned desirable results, and having as a part thereof, uniquely arranged apparatus which is associated with an electric switch in a manner so as to effectively and efficiently operate said switch at times predetermined by the operator.

Another aim of the instant invention is the provision of a time switch for radios or electrical devices, having a switch interposed in the circuit thereof, that has as a part thereof, a driven shaft geared to a drive shaft for rotation thereby, said driven shaft carrying hollow shafts and a switch lever operating cam, all specially disposed with respect to a setting shaft that has parts associated therewith which combine with the driven shaft and its supported elements in presenting an assembly that is simple, effective and inexpensive and extremely desirable.

The specific arrangement of parts and their association with a conventional electric switch constitutes further and minor objects of the invention, and one embodiment of the time switch is illustrated in the accompanying drawings, wherein:

Figure 1 is a front elevation of a time switch unit made to embody the present invention.

Fig. 2 is a horizontal, central section through the same, taken on line II—II of Fig. 1.

Fig. 3 is an irregular, vertical, sectional view through the time switch, taken on line III—III of Fig. 2.

Fig. 4 is an irregular, vertical, cross sectional view, taken on line IV—IV of Fig. 2.

Fig. 5 is a face view of one part of the electric switch employed in the time switch assembly.

Fig. 6 is a face view of another part of the electric switch, and,

Fig. 7 is a vertical, sectional view through the electric switch, taken on line VII—VII of Fig. 5.

The principal object of this invention is the provision of a time switch usable with radio receiving sets, and the electric switch built into

this time switch may be employed in lieu of the electric switch usually used in a radio set. When the electric switch of this time switch is used to make and break the circuit supplying energy to the radio receiving set, the said electric switch is interposed in the circuit through the medium of wires 10 and 12, connected to points 14 and 16 respectively. These said points are carried by specially formed blocks of insulating material 18 and 20, the abutting faces of which are serrated on an extremely large scale so that the high portions of one block will nest in the low portion of the other block. Whenever the complementary serrations of blocks 18 and 20 are together, as illustrated in Fig. 2, points 14 and 16 are in contact to close the circuit through wires 10 and 12.

Block 18 is stationarily supported by bracket 22 and block 20 is mounted at one end of rod 24 that extends into case 26 through the front panel 28 thereof. A knob 30 is provided on the outer end of rod 24. A ratchet 32, rigid on rod 24, transmits the force of spring 34 to rod 24 to maintain blocks 18 and 20 in the closed position, shown in Fig. 2. A bearing bracket 36, secured to case 26, engages the other end of spring 34. Rod 24 is rotatably journaled in front panel 28 and bearing bracket 36 and is provided with a ring 38 that is in wiping contact with finger 40 connected to wire 12. Clips 42 join ring 38 with contacts 16 to the end that when rod 24 is rotated, wires 10 and 12 may be connected or disconnected, depending upon the opposed or non-opposed relation between contacts 14 of block 18 and contacts 16 of block 20. Every other position offsets points 14 and 16 so that as rod 24 is turned, the switch is alternately on and off and no return of the rod and associated parts to a point of beginning is necessary.

Ratchet 32 is operated to rotate rod 24 automatically through the medium of the hereinafter described parts. Each switch operating unit, however, has a switch lever 44 provided with a laterally extending head 46 and formed with a hooked portion 48, as illustrated in Fig. 3. Lever 44 is pivoted to frame 50 as at 52 and a link 54 has one end pivotally joined as at 56 to a portion of lever 44 below pivot point 52. The other end of link 54 is joined to a spring 58 which maintains a tendency to pull link 54 in a direction so as to cause dog 60 to engage the teeth of ratchet 32 and rotate rod 24.

This dog 60 is yieldably maintained in contact with one of the teeth of ratchet 32 by a

spring 62, and dog 60 is so formed that when link 54 is drawn back from the position shown in dotted lines of Fig. 3 to the position shown in full lines thereof the dog will ride over the teeth of ratchet 32.

It is desirable to associate the conventional electric clock 64 with this time switch so that in setting the same, comparison may be made with a clock conveniently at hand. This clock 10 64 is no different from the conventional and ordinary clock and, therefore, further explanation is unnecessary.

In the embodiment of the invention illustrated, two complete setting units have been illustrated. Each works precisely the same as the other, and it will be obvious to one skilled in the art how the two units may be set to turn the electric switch first on and then off or vice-versa. The time elapsing between these two actions 20 may be governed by the operator in setting the apparatus, and an explanation of one of the units will clarify the manner of employing this invention.

A drive shaft 66 is operated by clockwork preferably of the synchronous motor type, not here shown. A driving gear 68 is rigid with shaft 66 and mounted thereon for rotation therewith. A solid driven shaft 70, journaled in the front panel and back wall of case 26, carries gear 72, which is always in mesh with driving gear 68. Gear 72 is at one end of shaft 70 and a pointer 74 is secured to the other end of this shaft. An outer tubular shaft 76 is rotatably carried by shaft 70 at the outer end thereof or that portion near front panel 30 28 and a dial 78 is secured to one end of this tubular shaft 76 immediately adjacent to pointer 74. Pointer 74 and dial 78 are normally in frictional engagement, and a spring 80 insures that this frictional engagement will be yieldable. Dial 78 has indicia thereon which presents a clock face so that when pointer 74 is set, the setting will compare with the time indicated by the pointer on clock 64.

A perforated disc 82 is secured to the inner end 45 of outer tubular shaft 76 to form one element of means for interconnecting the proximal ends of said outer tubular shaft 76, and a similar inner tubular shaft 84, which is rotatably carried by shaft 70. A friction wheel 86 is secured to one end 50 of tubular shaft 84 and is provided with a tooth 88 that engages perforation 90 of disc 82, as hereinafter set down. A clutch plate 92 is carried by the end of tubular shaft 84 adjacent to gear 72, and a spring 94 yieldably urges clutch plate 92 55 against the face of gear 72.

Inner tubular shaft 84 has a cam 96 thereon which is provided with a recess 98 adapted to receive head 46 of switch lever 44, as later described. A setting shaft 100, journaled for rotation and longitudinal reciprocation, has a knob 102 on the projected end thereof and is yieldably maintained at one end of its path of travel by a spring 104. A friction wheel 106, disposed so as to engage friction wheel 86, is mounted on setting shaft 100, as is a specially formed cone 108 that functions with hooked portion 48 of switch lever 44.

A cylindrical portion 110 is created on cone 108 and when lever 44 and cone 108 are in the relative positions shown in the left hand unit of Fig. 2, cam 96 cannot operate lever 44. Setting rod 100 is yieldably held, so that cone and lever 108 and 44 render the unit inoperative. Such holding is 70 accomplished by dog 112, which has a spring 114 75 associated therewith. When ear 116 is moved

past dog 112, the latter will preclude longitudinal movement of setting shaft 100 until the operator pulls out on knob 102 to draw ear 116 past dog 112. When dog 112 is functioning, spring 104 is expanded its full length.

Operation.—Assuming that the time is 12:15 p. m., as indicated by clock 64, and that it is desired to open the electric switch for the purpose of stopping the radio at 1:15, or one hour hence. Setting shaft 100 is moved outwardly longitudinally by grasping knob 102 and compressing spring 104. Such movement will draw together wheels 86 and 106 and will further join together outer tubular shaft 76 and inner tubular shaft 84 by moving pin 88 into perforation 90 of disc 82. Switch lever 44 will be moved to the position shown in full lines of Fig. 3 because the inclined face of cone 108 will engage the hooked portion 48 of lever 44 to not only swing head 46 out of recess 98, but to distend spring 58 and move dog 60 into engagement with one of the teeth of ratchet 32. Knob 102 is then rotated so as to impart rotary motion to dial 78 through the inter-engagement of 106, 86, 88, 90, 92 and 76. When the pointer 74 reaches the position indicating 1:15, or one hour later than the actual time as indicated by clock 64, the rotary action is stopped. Such rotary action, however, has turned cam 96 through the interconnection of parts 100, 106, 86 and 84. Gear 72, and therefore pointer 74, have 30 not turned because the friction between clutch plate 92 and gear 72 is not strong enough to overcome the holding action which driving gear 68 has upon gear 72. When setting shaft 100 is released by the operator, spring 104 will draw cone 108 to a point where hooked portion 48 of switch lever 44 is in a plane intersecting the point of smallest diameter on the cone and therefore freeing switch lever 44 so that head 46 is drawn into frictional engagement with the annular face 118 of cam 96 by spring 58. When setting shaft 100 is freed by the operator, friction wheels 106 and 86 are moved apart and disc 82 is no longer engaged by tooth 88 on wheel 86. As driving gear 68 continues to rotate gear 72, inner tubular shaft 84 45 will be rotated to turn cam 96 in the direction of the arrow shown in Fig. 3, and when recess 98 receives head 46, the movement of the parts under the force exerted by spring 58 will rotate ratchet 32 and rod 24 so as to break the electrical connection in the electric switch and, therefore, turn the radio off.

Manifestly, modifications and changes might be made in constructing a time switch in accordance with this invention without departing from the spirit thereof or scope of the appended claims.

Having thus described the invention, what is claimed as new and desired to be secured by Letters Patent is:

1. In a time switch of the character described having a driving gear and an electric switch, a driven shaft; a gear on one end of the driven shaft in mesh with the driving gear whereby to rotate the driven shaft a portion of a complete revolution in a predetermined length of time; a cam, provided with a recess, carried by the driven shaft; a switch lever having operable connection with the electric switch pivotally mounted adjacent to the cam and having a head adapted to enter said recess when the latter is in opposed relation with said head; an outer tubular shaft rotatably mounted upon said driven shaft near its other end; a dial having a clock face thereon secured to the outer tubular shaft; a pointer carried by the driven shaft at said other end.

- and adapted to travel over said clock face; a spring to yieldably hold the dial and pointer in frictional engagement; and settable means for simultaneously setting said settable means and said cam with respect to the pointer and head of the switch lever respectively, said dial and pointer being moved together about the axis of said driven shaft during operation of the time switch.
2. In a time switch of the character described having a driving gear and an electric switch, a driven shaft; a gear on one end of the driven shaft in mesh with the driving gear whereby to rotate the driven shaft a portion of a complete revolution in a predetermined length of time; a cam, provided with a recess, carried by the driven shaft; a switch lever having operable connection with the electric switch pivotally mounted adjacent to the cam and having a head adapted to enter said recess when the latter is in aligned relation with said head; an outer tubular shaft rotatably mounted upon said driven shaft near its other end; a dial having a clock face thereon secured to the outer tubular shaft; a pointer carried by the driven shaft at said other end; a spring to yieldably hold the dial and pointer in frictional engagement when in the normal position; a manually reciprocable and rotatable setting shaft; a member on the setting shaft for moving the head of said switch lever out of engagement with the recess in said cam when the shaft is at one end of its path of travel; and means interconnecting said setting shaft and said outer tubular shaft when the setting shaft is at said one end of its path of travel whereby the dial may be moved with respect to said pointer as the switch lever is disengaged from the recess in the cam.
3. In a time switch of the character described having a driving gear and an electric switch, a driven shaft; a gear on one end of the driven shaft in mesh with the driving gear whereby to rotate the driven shaft a portion of a complete revolution in a predetermined length of time; a pointer carried by the shaft at the other end thereof; an inner tubular shaft rotatably carried by the driven shaft; a clutch plate on the tubular shaft and in frictional engagement with the gear on the driven shaft; a spring to yieldably maintain the said plate against said gear; a cam provided with a recess mounted on the inner tubular shaft; an outer tubular shaft rotatably carried by the driven shaft; a dial on the said outer tubular shaft in juxtaposition to the pointer; a switch lever operable by the recessed portion of the cam; means for coupling together the proximal ends of the inner and outer tubular shafts; and manually operable setting mechanism adapted to render effective the coupling means to set the dial with respect to said pointer and to set the cam at a desired position with respect to the switch lever.
4. In a time switch of the character described having a driving gear and an electric switch, a driven shaft; a gear on one end of the driven shaft in mesh with the driving gear whereby to rotate the driven shaft a portion of a complete revolution in a predetermined length of time; a pointer carried by the shaft at the other end thereof; an inner tubular shaft rotatably carried by the driven shaft; a clutch plate on the tubular shaft and in frictional engagement with the gear on the driven shaft; a spring to yieldably maintain the said plate against said gear; a cam provided with a recess mounted on the inner tubular shaft; an outer tubular shaft rotatably carried by the driven shaft; a dial on the said outer tubular shaft in juxtaposition to the pointer; a switch lever operable by a spring; a perforated disc on the outer tubular shaft; a friction wheel on the inner tubular shaft having a projection for entering the perforation of said disc; a rotatable and reciprocable setting shaft; a friction wheel on the setting shaft to engage the first mentioned friction wheel when the setting shaft is at one end of its path of travel; and a cone on the setting shaft having an inclined face for engaging the switch lever to move the same out of the recess in the cam as the setting shaft is moved toward said one end of its path of travel, said switch lever having a hooked portion partially circumscribing said cone, said cone having a cylindrical portion formed thereon concentric with the said hooked portion and substantially the same diameter as
- inner tubular shaft; an outer tubular shaft rotatably carried by the driven shaft; a dial on the said outer tubular shaft in juxtaposition to the pointer, a switch lever operable by the recessed portion of the cam; means for coupling together the proximal ends of the inner and outer tubular shafts; and manually operable setting mechanism adapted to render effective the coupling means to set the dial with respect to said pointer and to set the cam at a desired position with respect to the switch lever, said setting mechanism having an element for withdrawing the switch lever from the cam recess.
5. In a time switch of the character described having a driving gear and an electric switch, a driven shaft; a gear on one end of the driven shaft in mesh with the driving gear whereby to rotate the driven shaft a portion of a complete revolution in a predetermined length of time; a pointer carried by the shaft at the other end thereof; an inner tubular shaft rotatably carried by the driven shaft; a clutch plate on the tubular shaft and in frictional engagement with the gear on the driven shaft; a spring to yieldably maintain the said plate against said gear; a cam provided with a recess mounted on the inner tubular shaft; an outer tubular shaft rotatably carried by the driven shaft; a dial on the said outer tubular shaft in juxtaposition to the pointer; a switch lever operable by a spring; a perforated disc on the outer tubular shaft; a friction wheel on the inner tubular shaft having a projection for entering the perforation of said disc; a rotatable and reciprocable setting shaft; a friction wheel on the setting shaft to engage the first mentioned friction wheel when the setting shaft is at one end of its path of travel; and a cone on the setting shaft having an inclined face for engaging the switch lever to move the same out of the recess in the cam as the setting shaft is moved toward said one end of its path of travel.
6. In a time switch of the character described having a driving gear and an electric switch, a driven shaft; a gear on one end of the driven shaft in mesh with the driving gear whereby to rotate the driven shaft a portion of a complete revolution in a predetermined length of time; a pointer carried by the shaft at the other end thereof; an inner tubular shaft rotatably carried by the driven shaft; a clutch plate on the tubular shaft and in frictional engagement with the gear on the driven shaft; a spring to yieldably maintain the said plate against said gear; a cam provided with a recess mounted on the inner tubular shaft; an outer tubular shaft rotatably carried by the driven shaft; a dial on the said outer tubular shaft in juxtaposition to the pointer; a switch lever operable by a spring; a perforated disc on the outer tubular shaft; a friction wheel on the inner tubular shaft having a projection for entering the perforation of said disc; a rotatable and reciprocable setting shaft; a friction wheel on the setting shaft to engage the first mentioned friction wheel when the setting shaft is at one end of its path of travel; and a cone on the setting shaft having an inclined face for engaging the switch lever to move the same out of the recess in the cam as the setting shaft is moved toward said one end of its path of travel, said switch lever having a hooked portion partially circumscribing said cone, said cone having a cylindrical portion formed thereon concentric with the said hooked portion and substantially the same diameter as

the hooked portion whereby the switch lever is held inoperative when the cylindrical portion of the cone is positioned so as to be partially circumscribing said switch lever.

- 5 7. In a time switch of the character described having a driving gear and an electric switch, a driven shaft; a gear on one end of the driven shaft in mesh with the driving gear whereby to rotate the driven shaft a portion of a complete revolution in a predetermined length of time; a pointer carried by the shaft at the other end thereof; an inner tubular shaft rotatably carried by the driven shaft; a clutch plate on the tubular shaft and in frictional engagement 10 with the gear on the driven shaft; a spring to yieldably maintain the said plate against said gear; a cam provided with a recess mounted on the inner tubular shaft; an outer tubular shaft rotatably carried by the driven shaft; a dial on 15 the said outer tubular shaft in juxtaposition to the pointer; a switch lever operable by a spring; a perforated disc on the outer tubular shaft; a 20

friction wheel on the inner tubular shaft having a projection for entering the perforation of said disc; a rotatable and reciprocable setting shaft; a friction wheel on the setting shaft to engage the first mentioned friction wheel when the setting shaft is at one end of its path of travel; and a cone on the setting shaft having an inclined face for engaging the switch lever to move the same out of the recess in the cam as the setting shaft is moved toward said one end of its path of travel, said switch lever having a hooked portion partially circumscribing said cone, said cone having a cylindrical portion formed thereon concentric with the said hooked portion and substantially the same diameter as the hooked portion whereby the switch lever is held inoperative when the cylindrical portion of the cone is positioned so as to be partially circumscribing said switch lever, said setting shaft having means for yieldably holding said cone in such position. 5 10 15 20
